Primary Examiner — Jasmine Mlinarcik(74) *Attorney, Agent, or Firm* — Keisling & Pieper PLC; David B. Pieper; Trent C. Keisling(57) **CLAIM**

The ornamental design for a head covering as shown and described.

DESCRIPTION

FIG. 1 is a top perspective view of a head covering showing my new design;

FIG. 2 is a top view thereof;

FIG. 3 is a bottom view thereof;

FIG. 4 is a front perspective view of the head covering shown in a position of use;

FIG. 5 is a right side perspective view thereof;

FIG. 6 is a left side perspective view thereof;

FIG. 7 is a back perspective view thereof; and,

FIG. 8 is a left side perspective view thereof, shown in an alternative position.

The broken line outline of the partial human figure in FIGS. 4-8 assists in illustrating how the head covering may appear when in a position of use, but forms no part of the claimed design. The broken line outline of the securing fastener along the band of the head covering in FIG. 7 forms no part of the claimed design.
